UNITED STATES PATENT OFFICE.

JOSEPH W. DEWS, OF WATERBURY, CONNECTICUT, ASSIGNOR TO SCOVILL MANUFACTURING COMPANY, OF WATERBURY, CONNECTICUT, A CORPORATION OF CONNECTICUT.

SNAP FASTENER.

Application filed May 16, 1923. Serial No. 639,845.

To all whom it may concern:

Be it known that I, JOSEPH W. DEWS, a citizen of the United States, residing at Waterbury, in the county of New Haven and 5 State of Connecticut, have invented a certain new and useful Improvement in Snap Fasteners, of which the following is a full, clear, and exact description.

This invention relates to that class of fasteners which comprises a male and a female member, or, as otherwise designated, a stud or head member and a socket member, in which the stud-engaging element in the 10 socket member is a wire spring which grasps 15 a groove in the stud, the socket being applicable to and detachable from the stud only by a tilting movement.

The invention consists of a novel form of stud-engaging spring, and novel features in 20 the arrangement of the spring on the base plate of the socket, as I will proceed now to explain and finally claim.

In the accompanying drawings illustrating the invention, in the several figures of 25 which like parts are similarly designated, Figure 1 is a plan view of a corner of a curtain to which the socket member is applied and also showing the head or stud in cross-section. Fig. 2 is a plan view of the base 30 plate of the socket with the spring in position. Fig. 3 shows in cross-section the attaching shell and the base plate detached. Fig. 4 is a cross-section showing the shell and base plate assembled and ready for attachment to a curtain, the sections in Figs. 3 and 4 being taken in the plane of line 3-4 of Fig. 2. Fig. 5 is a perspective view 35 of the base plate detached. Fig. 6 is a top plan view and Fig. 7 is an elevation of one 40 form of head or stud of the screw type.

The base plate 1, has a central hole 2 for the entrance of the head or stud, and it is also provided with slots 3 and 4 in its rim to receive the prongs 6 and 5 respectively of 45 the shell or cap 7, the prongs 5 serving as assembly means for the shell and base plate, and prongs 6 serving as attaching means for setting the socket on a curtain or other article. The shell is provided with a central hole 8 through which the tip of the head or stud projects, although, of course, the shell may be otherwise made, perforate or imperforate, to suit the convenience of the user.

The base plate is provided with the parallel 50 upturned lugs 9 near one edge and also

with the parallel and upturned lugs 10 adjacent to the central hole 2 to engage the spring, hold it in place, and prevent any undue expansion which might tend to destroy it or impair its elasticity. These lugs 9 and 10 also serve to engage and support the shell and prevent it from interfering with the free action of the spring in case of injury to the socket. This shell also has a rim 11, Fig. 3, which engages the base plate and tends 60 to space the shell from the base plate sufficiently to permit of the reaction of the spring.

The spring referred to comprises a circular portion 12, the ends 13 of which are turned in towards the center of the circle and for a portion of their length are parallel and in contact and then diverge to form the shoulders 14 which project slightly within the area of the central holes in the shell 70 and the base plate, and then are carried across in parallelism, as at 15, to straddle the hole 2, and finally the ends 16 are bent outwardly and backwardly so as to contact with the circular portion 12, so that when 80 the fastener stud enters or leaves the socket, these ends function resiliently. By this arrangement, it is possible to use lighter and more easily formed wire than in those cases 85 where the resilience of the ends is not utilized.

The parallel portions 13 which are in contact, are engaged by the lugs 9, and these lugs not only serve to hold the ends of the spring together, but they also serve to prevent the rotation of the spring within the fastener. In other words, these lugs in their engagement with the spring serve as stops to hold the spring in proper position 90 within the socket. The lugs 9 are in effect 95 the fulcrum where the resilient action of the spring begins. In the absence of such lugs, a spring of the character herein illustrated will not give equivalent results unless made of wire very much heavier than it is desirable or practicable to use. Thus 100 in the arrangement shown, there is a saving of material in the spring, and as a light wire may be used, the spring is easier to form or manufacture.

The lugs 10 aid in supporting the front shell of the socket as already described; and in addition they prevent the wire from being deformed by an opening pull applied on either side of the socket. By the term 110

"either side" is meant approximately where the socket circumference would be intersected by a straight line running through the middle of both of these lugs.

5 As the lugs 9 and 10 are well distributed at points beneath the shell, it follows that the shell is well supported against the damaging effects of blows on the socket, and not only so, but the use of these well distributed lugs permits the use of lighter metal in forming the shell.

10 As will be understood, the socket of this invention is of the type which can be opened only by a pull exerted on one side of the 15 socket, and in this particular invention the pull side is opposite that on which the lugs 9 are placed. If the pull be applied on the lug side, these lugs hold the two wires between them and prevent their expansion 20 under the strain of connecting the fastener members and their disconnection, and they also prevent displacement of the spring within the socket.

25 Any usual or approved male or stud or head member may be used in connection with the socket member of the character described, but I have shown one illustration of the screw-held type of male, stud, or head member in Figs. 6 and 7, and in this illustration 17 is the attaching device in the form of a screw and on this screw is mounted a polygonal portion 18 by means of which the screw may be driven. Above the polygonal portion is the conoidal tip 19 and below this 35 tip is a groove 20 which is engaged by the spaced-apart reentrant ends of the spring, and particularly by the shoulders 14 and adjacent parts.

40 As already stated, it is possible to effect engagement of socket and stud in only one way, and that is by bringing these parts into cooperative relation when the socket member is tilted upwardly away from that side on which the word "LIFT" occurs in Fig. 1. 45 When so correlated the socket member may be pressed down upon the stud and the free reentrant ends of the spring are free to yield for the passage of the tip 19 and then to spring back into the groove 20 and so effect 50 a very secure separable connection with the stud. To disconnect the socket it is tilted in a direction away from the side on which the word "LIFT" occurs. In other words, the socket member is moved in the same way 55 to effect connection with the stud and disconnection from it.

Variations in details of construction are permissible within the spirit of the invention and the scope of the claims following.

60 What I claim is:—

1. In a snap fastener socket member, a stud-engaging spring composed of a circular outer portion having reentrant ends in par-

allel contact for a portion of their length and then divergent to form stud-engaging shoulders and extending farther within the circular portion in parallel relation and having their tips turned outwardly into contact with the circular outer portion so that when the fastener stud enters or leaves the socket 70 these terminal portions function resiliently.

2. In a snap fastener socket member, a base plate and a shell, combined with an interposed stud-engaging spring mounted upon the base plate and covered by the shell, 75 said spring having an outer circular portion with reentrant ends in parallel contact for a portion of their length and then diverging to form stud-engaging shoulders and extending farther within the circular portion in 80 parallel relation and having their tips turned outwardly toward the circular portion.

3. In a snap fastener socket member, a base plate and a shell, combined with an interposed stud-engaging spring mounted upon the base plate and covered by the shell, 85 said spring having an outer circular portion with reentrant ends in parallel contact for a portion of their length and then diverging to form stud-engaging shoulders and extending 90 farther within the circular portion in parallel relation and having their tips turned outwardly toward the circular portion, said base plate provided with lugs to engage the parallel contact portions of the spring and other lugs in the path of movement of the diverged parallel portions of the spring.

4. In a snap fastener socket member, a base plate and a shell, combined with an interposed stud-engaging spring mounted upon the base plate and covered by the shell, 100 said spring having an outer circular portion with reentrant ends in parallel contact for a portion of their length and then diverging to form stud-engaging shoulders and extending 105 farther within the circular portion in parallel relation and having their tips turned outwardly in opposite directions toward the circular portion, said base plate having pairs of upstanding lugs arranged to come within the circular portion of the spring, one pair of lugs engaging the contacting portions of the spring ends and the other pair arranged opposite the divergent portions of such ends, said lugs serving as 110 stops for the reentrant ends of the spring and also serving to support the shell above the spring.

In testimony whereof I have hereunto set 115 my hand this 15th day of May A. D. 1923.

JOSEPH W. DEWS.
